CLAIM

(57) The ornamental design for a sliding door handle set, as shown and described.

DESCRIPTION

FIG. 1 is a perspective view of a sliding door handle set showing the new design;

FIG. 2 is another perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a perspective view of the sliding door handle set of FIG. 1, shown with environment; and,

FIG. 10 is another perspective view thereof, shown in an alternate state.

The broken line showing of a sliding door handle set is for the purpose of illustrating portions of the article and forms no part of the claimed design. The broken line showing of a door in FIGS. 9 and 10 is for the purpose of illustrating environmental structure and forms no part of the claimed design.
